RADIAL CONSTRUCTION OF FOUNDATION
GARMENTSJoseph Leonard, Allentown, Pa., assignor to Mona
Lisa Foundations, Inc., a corporation of New
York

Application January 23, 1952, Serial No. 267,853

3 Claims. (Cl. 2-37)

1

This invention relates to improvements in the construction of foundation garments, such as girdles and the like.

I have found that I can combine extremely effective control of the abdominal region with great simplicity in construction by incorporating overlapping elastic panels in the garment in proximity to the abdominal region provided each such panel consists of material which is stretchable in primarily one direction and when assembled in the garment the panels are superimposed so that their lines of stretchability are oppositely disposed and form acute angles relative to the horizontal axis of the garment. In such case, tension in the superimposed layers tends to act radially and provides remarkably effective control over the abdomen. In effect, the garment acts as if it were constructed of material having radially disposed lines of stretchability when the material actually used stretches in a single direction.

In manufacturing this garment I provide a relatively narrow panel member in the front of the garment which is either inelastic or is stretchable only vertically but not horizontally or circumferentially. On either side of this front panel member I incorporate the particular elastic panel construction of this invention.

A portion of such panel is cut and formed of material which is primarily stretchable in a single direction and this is attached to the side of the front panel member so that it is stretchable at an angle between about 8 degrees to 22 degrees relative to the horizontal axis of the garment. Another section, cut from the same material and likewise stretchable in primarily one direction, is attached to the same side of the front panel member but with its line of stretchability oppositely disposed relative to the other panel and so that it is partially superimposed on the other panel. This second section is attached to the side of the front panel member with its line of stretchability forming an angle of between about 8 degrees and 22 degrees with the horizontal axis of the garment but in the opposite direction relative to the first elastic panel.

Each of the aforesaid panel sections is cut so that it covers more than one-half, but less than the entire height of the panel. The panel sections thus overlap and are superimposed in the mid-portion of the garment.

Preferably, the two overlapping elastic panel sections are assembled in the garment with the lower edge of one section and the upper edge of the other section forming a taper which outlines the superimposed area, with the taper nar-

2

rowing toward the front of the garment. In the superimposed portion of the garment the lines of stretchability in each panel section are disposed at an angle between about 16 degrees and 44 degrees relative to each other but between about 8 degrees and 22 degrees relative to the horizontal axis of the garment. As a result the garment exerts effective elastic tension radially over the abdominal region.

10 In the drawing Fig. 1 is a front elevation showing the structure of my invention embodied in a girdle and Fig. 2 is a rear elevation of the same garment; Fig. 3 is a front elevation showing a modified form of my invention; Fig. 4 is a rear elevation of the garment of Fig. 3; and Fig. 5 is a fragmentary cross-section on the line 5-5 of Fig. 3.

15 The garment 10 consists of a plurality of panel members which are attached to each other circumferentially to form the girdle. The panel members are shown at 12, 13, 14, 15, 16, and 17.

20 The front panel member 12 and the back panel member 17 are made of inelastic material (or of elastic material which is stretchable vertically but not horizontally or circumferentially). At either side of back panel member 17 panel members 15 and 16 (formed of elastic material which is stretchable horizontally and circumferentially) are attached. Back panel member 17 may 25 carry a separate top edge portion 28 (as shown in the drawing) above the waistline which is stretchable horizontally.

28 In Fig. 1 panel members 13 and 14, on either side of panel member 12, incorporate the particular structure of this invention.

30 The arrows in the drawing indicate the line of direction of stretchability of the various panel sections or panel members. In this application I use the term "panel section" to indicate a layer of fabric which is attached to another layer to form a panel member which runs from the top to bottom of the garment. Specifically, panel sections 18 and 20 are attached to each other to 35 form the panel member 13; and panel sections 22 and 24 are attached to form panel member 14. Panel members 12 and 17 consist of fabric members which form the entire panel member without overlapping.

35 In making foundation garments embodying this invention I prefer to use an elastic fabric which is known in the trade as leno elastic. This is a fabric in which the rubber strand runs in one direction and is therefore primarily stretchable in that direction. In this type of material 40 the stretchability in a direction at right angles

to the rubber is limited although the fabric may possess some slight stretch in that direction.

Panel member 13 is formed by attaching together two partially superimposed panel sections 18 and 20. Panel section 18 is stretchable in a single direction and is attached to the garment so that its line of stretchability is at an acute angle relative to the horizontal axis of the garment. This is shown by the arrow on the drawing. Likewise, panel section 20 is attached to the garment so that its line of stretchability is oppositely disposed relative to that of section 18. Panel sections 18 and 20 overlap in the midportion of the panel member, as indicated by the crossed arrows, and this shows the superimposition of the respective lines of stretchability of the material of panel sections 18 and 20.

The superimposed layers are attached to the garment so that intermediate edges 21 and 23 form a tapered mid-section with the taper narrowing toward the front of the garment.

The same construction is used in panel member 14 on the other side of panel member 12.

Panel sections 22 and 24 correspond to panel sections 18 and 20 and are superimposed in the midportion of the garment so that their lines of stretchability (as shown by the crossed arrows) are oppositely disposed in the same manner as in panel member 13.

The back panel member 17 is made of material which is inelastic horizontally but elastic vertically. The back panel member 17 carries a top portion 28 above the waistline which is stretchable horizontally.

On either side of back panel member 17, panel members 15 and 16 are attached and these panel members are also attached to the side edges of panel members 13 and 14 respectively. In panel members 15 and 16 the elastic material may be stretchable horizontally and circumferentially. These panel members may also contain sections which are superimposed in the same manner as panel members 13 and 14 except that as shown in Fig. 2 the line of stretchability of the fabric in panel members 15 and 16 extends circumferentially and is not oppositely disposed as in panel members 13 and 14. A tapered portion may be formed in panel members 15 and 16 with the taper narrowing toward the back of the garment.

A conventional zipper member 27 is shown at the side of panel 15.

In Fig. 3 I show a structure which is the same as the structure of Fig. 1 except that panel members 32 and 34 (embodimenting the structure of this invention) extend around and attach directly to back panel member 36. In such case the tapered mid-portion extends from the side edges of back member 36 to the side edges of front panel member 31 with the taper narrowing all the way toward the front of the garment.

Fig. 5 shows cross-sectional detail of the superimposed layers of the fabric sections in panel member 34 where fabric section 34 is superimposed in the mid-portion on fabric section 35. A conventional zipper member 37 is shown in panel member 31.

In each case, the panel members are joined together circumferentially by sewing or stitching the panels together with or without binding tape or the like.

I have found that a foundation garment embodying the particular panel construction of this invention acts uniformly and effectively over the abdominal region in response to stresses

applied to the garment and I believe this control is a direct result of the radial distribution of these stresses in the garment as pointed out above. I have described preferred embodiments of my invention but changes in detail may be made without altering the basic structure of my invention.

What I claim is:

1. In a foundation garment having a plurality of panel members joined together to form an integral garment, the combination which comprises a front fabric panel member running lengthwise from the top to the bottom of the garment made of material which is substantially inelastic horizontally and circumferentially, a back panel member running lengthwise from the top to the bottom of the garment comprising a bottom portion made of material which is inelastic horizontally and circumferentially and a top portion made of material which is elastic primarily in a horizontal and circumferential direction, said bottom portion extending upwardly through a major portion of the length of the garment and said bottom and top portions being joined together along their contiguous edges in a circumferential direction, a pair of side panel members positioned in the rear of the garment which run from the top to the bottom of the garment each of which is positioned at opposite sides of the back panel members and joined to the back panel members along their contiguous side edges in a vertical direction, each of said side panel members being made of material which is primarily elastic in a circumferential and horizontal direction, a second pair of side panel members positioned in the front of the garment, running lengthwise from the top to the bottom of the garment each of which is positioned between opposite side edges of the front panel member and the free side edge of one of said side panel members in the rear of the garment, said front side panel members being joined to the front panel member and side panel members in the rear of the garment along their contiguous side edges in a vertical direction from the top to the bottom of the garment to form an integral structure, each of said front side panel members consisting of two panel sections, a bottom panel section connecting the lower side portion of the front panel member with the lower side portion of the side panel members in the rear of the garment and a top panel section connecting the top side portion of the front panel member with the top side portion of the side panel member in the rear of the garment, each of said panel sections being long enough to extend lengthwise over more than one half but less than the entire length of the garment from top to bottom so that the lower portion of the top panel section is superimposed over the top portion of the bottom panel section throughout the entire width of the front side panel members, each of said top and bottom panel sections having their bottom and top edges respectively cut on a bias so that the areas in the front side panel members in which the panel sections are superimposed taper down along their top and bottom edges from the side panel members in the rear of the garment to the side of the front panel member, each of said panel sections being made of a material which is elastic primarily in one direction, said top panel sections being so positioned in the garment that their lines of stretchability are at an acute angle relative to the horizontal axis of the garment and said bottom panel sections being so positioned in the gar-

ment that their lines of stretchability are also at an acute angle relative to the horizontal axis of the garment but oppositely disposed relative to the top panel sections, said top panel sections having their bottom edges attached to the body of the bottom panel sections along the entire width of the panel member, said bottom panel sections having their top edges attached to the body of the top panel sections along the entire width of the panel members and each of said panel sections having their opposite side edges joined in a vertical direction to contiguous edges of the front and side panel members in the rear of the garment respectively, whereby stresses applied to the front panel member tend to be resisted circumferentially by the elastic tension in the area of the front side panel members where the panel sections are superimposed and radially in the top and bottom portions of the front side panel members where the panel is formed of a single panel section.

2. A structure as specified in claim 1 in which each side panel member in the rear of the garment comprises two panel sections each of which is long enough to extend lengthwise over more than one half but less than the entire length of the garment from top to bottom so that the lower portion of the top panel section is superimposed over the top portion of the bottom panel section throughout the entire width of the panel member each of said top and bottom panel sections having its respective bottom and top portions cut on a bias so that the areas in the panel members in which the panel sections are superimposed taper down along their top and bottom edges from the front side panel members to the sides of the back panel member, each of said panel sections being made of a material which is elastic primarily in one direction and said panel sections being so positioned in the garment that the line of stretchability of both panel sections is in a circumferential direction in the garment and said top and bottom panel sections being joined along the entire length of their side edges to contiguous edges of the front side panel members and back panel member and said top panel sections having their bottom edges attached to the body of the bottom panel sections along the entire width of the panel members and said bottom panel sections having their top edges attached to the body of the top panel sections along the entire width of the panel member.

3. In a foundation garment having a plurality of panel members joined together to form an integral garment, the combination which comprises a front fabric panel member running lengthwise from the top to the bottom of the garment which consists of material which is substantially inelastic horizontally and circumferentially, a back panel member running lengthwise from the top to the bottom of the garment comprising a bottom portion made of material which is inelastic horizontally and circumferentially and a top portion made of material which is elastic primarily in a horizontal and circumferential direction, said bottom portion extending upwardly through a major portion of the length of the garment and said bottom and top portions being joined to-

gether along their contiguous edges in a circumferential direction, a pair of side panel members running lengthwise from the top to the bottom of the garment, each of which is positioned in the garment with one side edge contiguous to a side edge of the front panel member and the second side edge contiguous to a free side edge of the back panel member, said side panel members having their side edges joined to the front and back panel members along contiguous edges lengthwise from the top to the bottom of the garment to form an integral structure, each of said side panel members consisting of two panel sections, a bottom panel section connecting the bottom side portion of the front panel member with the bottom side portion of the back panel member and a top panel section connecting the top side portion of the front panel member with the top side portion of the back panel member each of said panel sections being long enough to extend lengthwise over more than one half but less than the entire length of the garment from top to bottom so that the lower portion of the top panel section is superimposed over the top portion of the bottom panel section throughout the entire width of the side panel members, each of said top and bottom panel sections having their bottom and top edges respectively cut on a bias so that the areas of the side panel members in which the sections are superimposed taper down along their top and bottom edges from the back panel member to the side of the front panel member, each of said panel sections being made of a material which is elastic primarily in one direction, said top panel sections being so positioned in the garment that their lines of stretchability are at an acute angle relative to the horizontal axis of the garment and said bottom panel sections being so positioned in the garment that their lines of stretchability are also at an acute angle to the horizontal axis of the garment but oppositely disposed relative to the top panel sections, said top panel sections having their bottom edges attached to the body of the bottom panel sections along the entire width of the side panel member and said bottom panel sections having their top edges attached to the body of the top panel sections along the entire width of the side panel members whereby stresses applied to the front panel member tend to be resisted circumferentially by the elastic tension in the area of the side panels where the panel sections are superimposed and radially in the top and bottom portions of the side panel members where they are formed of a single panel section.
